PUPPET DOLL

Leba C. Secter, Winnipeg, Manitoba, Canada

Application June 21, 1951, Serial No. 15,618

Term of patent 14 years

(Cl. D34—2)

To all whom it may concern:

Be it known, that I, Leba C. Secter, a citizen of Canada and a resident of the city of Winnipeg, Province of Manitoba, Dominion of Canada, have invented a new, original, and ornamental Design for a Puppet Doll, of which the following is a specification, reference being had to the accompanying drawings, forming part thereof, in which—

Figure 1 is a front view of a puppet doll showing my new design.

Figure 2 is a fragmentary rear view thereof; and

Figure 3 is a side view to a reduced scale.

I claim:

The ornamental design for a puppet doll, as shown.

LEBA C. SECTER.
